UNITED STATES PATENT OFFICE.

NAPOLEON J. PERRY, OF NASHVILLE, TENNESSEE, ASSIGNOR TO MAY HOSIERY MILLS, OF NASHVILLE, TENNESSEE, A CORPORATION OF TENNESSEE.

KNITTING MACHINE.

Application filed February 6, 1917, Serial No. 146,917. Renewed April 10, 1928.

My invention relates to knitting machines and consists in the combinations and arrangements of elements hereinafter described and particularly set forth in the accompanying claims.

The invention has for its purpose to provide a knitting machine convertible to knit either plain or rib fabric, to the end that articles of apparel (particularly hosiery) may be completely knitted from the toe to the top of the hose without requiring the transference of the article from one machine to another, as is now the practice.

Another purpose of the invention is to equip a plain knitting machine with apparatus for rib knitting, wherein said rib knitting apparatus is automatically controlled by pattern mechanism.

The invention further contemplates the provision of a pattern form that is actuated through the aforesaid control of the plain knitting machine, that will bring the rib knitting mechanism into operation to knit rib knitting at the proper periods in the manufacture of the article, and which is adapted to be altered or changed at will.

The invention, as disclosed herein, is adapted for attachment to any standard type of circular knitting machine, and the range of adjustment, timing, and combinations of the several elements, is such that the equipped machine is capable of manufacturing a wide variety of articles by plain knitting, rib knitting, circular knitting, reciprocal knitting, or any combination of these.

The invention is disclosed by way of illustration in the accompanying drawings, wherein

Figure 1 is a front elevational view of the machine complete.

Figure 1^a shows one type of stocking knitted by the machine.

Figure 2 a top plan view of the machine.

Figure 3 a transverse sectional view taken on the line 3—3 of Figure 1.

Figure 4 a sectional view on the line 4—4 of Figure 1.

Figure 5 a horizontal sectional view taken on the line 5—5 of Figure 3, and with certain parts omitted.

Figure 6 a central sectional view of the dial and dial cap taken on the line 6—6 of Figure 8.

Figure 7 a similar view taken on the line 55 7—7 of Figure 8.

Figure 8 an inverted plan view of the dial cap,

Figure 9 a diagrammatic view, partly broken away, of the dial and showing the 60 needles in different positions of operation.

Figure 10 a detail view of a cam element of the dial cap,

Figure 11 a detail sectional view showing the tensioning device for the movable guide 65 members,

Figure 12 a detail horizontal sectional view of the cylinder and sinker ring, showing the dial control lugs in modified form,

Figure 13 an enlarged detail view of one 70 of the dial cap cam actuating devices,

Figure 14 a similar view of the other dial cap cam actuating device, and

Figure 15 a top plan view of the device 75 shown in Figure 14.

While the invention is in no sense to be considered as limited to any particular type of machine, the novel elements of mechanism have been illustrated as a matter of convenience in connection with a machine of the type having rotary cams and a fixed needle cylinder, substantially similar to that shown in the patent to Mayo, 726,178, April 21, 1903, to which reference may be had for fuller explanation of details of the structure improved upon.

Referring to the construction in further detail, and wherein like reference characters indicate corresponding parts in the different figures, 25 designates the frame of any 90 standard plain knitting machine, having a driving shaft 26 journaled therein and adapted to be driven through a suitable source of power by a pulley arrangement 27. Said driving shaft is fitted with clutch elements 28 and 29 for rotating the knitting head 30 for circular knitting through the bevel gears 31 (only one being shown); or said knitting head may be oscillated for reciprocal knitting, through the clutch 100 elements 29 and 33.

The transmission for operating the knitting head to knit by reciprocal knitting comprises a pinion 34 coupled to rotate with the shaft 26 through the clutches (29 and 33) and meshing (Fig. 3) with a larger pinion 35 journaled on the shaft 36. Said pinion 35 carries a crank-arm 37 connected

with the connecting-rod 38 to operate the gear segment 39; and said segment meshes with the gear wheel 40 (Figure 4) to impart oscillation thereto. Said gear wheel 40 is loosely mounted on the shaft 26 and therefore runs idly except when the clutch elements 28 and 29 are coupled. This coupling engagement (28 and 29) gives oscillation to shaft 26 and a like motion to the bevel gear 31 and operates the knitting head for reciprocating knitting. The means for changing from rotary to reciprocating knitting is the same as in the patent to Mayo, 726,178. The clutch element 29 is actuated to 10 connect with either of the clutch elements 28 or 33 for imparting rotation or oscillation to the knitting head for circular or reciprocating knitting, through the clutch arm 41 fulcrumed on the frame at 42 and operated 15 through engagement with the cam wheel 43 that is fixed to a second shaft 44 mounted on the frame 25.

The cam wheel 43 is adapted to be operated intermittently from the driving shaft, 25 through the following mechanism; sprocket chain 48 travels on a sprocket wheel 47 integral with ratchet 45 and loosely mounted on hub 46 of cam wheel 43; and said chain constitutes the time controlled element of 30 the machine. The ratchet wheel 45 is intermittently turned by the pawl 49 carried by the arm 50 fulcrumed on the frame at 51, and movement is imparted to said arm through the anti-friction roller 252 (Fig. 3) 35 mounted on gear-segment 39 at the lower end of the connecting rod 38. A retraction spring 54, anchored to the frame, co-operates with said roller 252 to move the pawl 49 continuously. With the mechanism thus described, only the ratchet wheel 45 and the sprocket wheel 47, carrying the chain 48 are 40 operated, i. e. the shaft 44 and the cam wheel 43 remain stationary for extended periods of time. Since the segment gear 39 operates 45 continuously ratchet wheel 45 is likewise operated continuously and the pattern chain 48 is therefore driven during rotary or reciprocating knitting.

The shaft 44 has a notched disk 55 fixed 50 thereon that is engaged by a pawl 56 mounted on the lever 57 that is fulcrumed to the frame at 58; and said lever derives movement from the hub 53 of the segment gear 39, through the cam 52, for moving the 55 arm in one direction, and the retraction spring 60 operates to return said arm. The pawl 56 is normally held inoperative by the dog 61 pivoted on the frame 25 (see Figure 5) and said dog is tensioned, by the 60 spring 59, to engage with one edge of the chain and is formed with a tail-piece 62 (see Figure 3) normally co-acting with the pin or stud 63 of the pawl 56, to hold the latter out of engagement with said notched 65 disk 55. The chain 48 is provided with

properly distributed lugs 64, whose function is to engage with dog 61 and lift the latter to release the pawl 56, when said pawl may engage with a notch on the disk 55 and impart movement thereto. Said disk 55 is 71 fixed to rotate with the cam wheel 43 and thereby impart movement to said cam wheel to actuate the clutch-shifting arm 41 to engage with one or the other of clutch elements 28 and 33, accordingly as the machine is to 71 operate by circular knitting or reciprocable knitting, and this is predetermined by the number and location of lugs 64 on the chain.

A second cam drum 65 (Figures 1 and 5) is fixed on the shaft 44 and has for its function to shift the cam plate (not shown) of the knitting head and to manipulate the yarn carrier (not shown), as in standard machines of this type. A notched disk 66 is secured to said cam drum 65 and is engaged to be operated by a pawl 67 mounted on the lever 68 that is, in turn, moved through engagement with the roller 268 mounted on the gear segment 39 (see Fig. 5); and a retraction spring 69, anchored to the frame, engages with said lever 68. The notches on the disk 66 are disposed to supplement the notches on the disk 55, to the end that the latter disk (55) will be moved during those periods when its own operating pawl 56 is inactive, i. e. the two disks 55 and 66 have their respective notches so located as to form virtually a single disk notched about its periphery. The disk 55 has, in fact, only four notches, and by this arrangement, the cam wheel 43 is moved that number of times to shift the clutch in accordance with the arrangement of lugs 64 on the chain 48; and the disk 55 must therefore be moved to make up for its blank periphery, and this is done by the notches in the disk 66 which are located angularly with respect to the blank periphery of said disk 55; and where there are notches on the disk 55, there are none on the disk 66. In other words, the disk and pawl (66 and 67) provide an auxiliary device for insuring the running of the machine in proper time. The main cam shaft 44 and pattern drum 65 and cam wheel 43 fast thereto are thus moved 1 when chain 48 through a high link 64 acts on the dog 61 to lower its tail 62, whereupon pawl 56 drives ratchet 55 one step. Then the continually acting pawl 67 moves ratchet 66 until a blank space on the ratchet 66 is reached. The chain having meantime released lever 61, pawl 56 is held out of engagement with ratchet 55 until another high link of the chain reaches dog 61. The pattern chain acts in the usual way to determine the periods of operation of the cam-shaft by holding its primary actuating pawl 56 out of action for comparatively long periods, and the cam-shaft controls the elements of the organized machine as above set forth. 1

The structure thus far described is old and forms no part of my invention except as certain parts co-operate with the elements of my improved structure. Certain novel features of the pattern mechanism are claimed in my copending application, Serial No. 346,681, filed December 22, 1919.

The attachment per se consists of a dial cam head having dial needles therein mounted on a ring gear, and said dial cam head consists of a pair of brackets or posts 70 mounted on two blocks 71, 71' that are secured to the cam ring gear 72 (Fig. 2) by the screws 73, or said posts may be mounted on the ring gear in any other suitable manner. A yoke piece 74 is mounted on said brackets 70, and has depending and fixed thereto a shaft 75 disposed concentrically with the stationary cylinder 76 of the cylinder needles (see Figures 1 and 12). A stationary dial 77, constructed to receive a plurality of dial needles 78, is fitted on the shaft 75 and located within the cylinder 76, and is held stationary during rotary knitting by engagement of its lug 79 (Figs. 6 and 12) against lug 80 on the sinker ring 81 secured to the needle cylinder 76, but is free to oscillate during the knitting of heels and toes. Such oscillation may be due to friction between the parts of the machine and the fabric and if only one lug 80 were present might carry lug 79 into the area of the forming fabric of a heel or toe pocket or the like, thus retarding the progress of that portion of the web most in need of acceleration. A second lug 80' is therefore placed on the sinker ring at a distance of approximately 180° from lug 80.

If the lugs 80 and 80' were placed close together at one side of the cylinder the friction of the fabric on dog 79 would be needlessly increased.

Lug 79 may be fixed to the dial (Fig. 6) or integral therewith (Fig. 12).

A dial cap 82 is secured to the shaft 75 and carries the elements for actuating the dial needles at the periods predetermined by the pattern forms 133 hereinafter referred to. Said elements consist of a pair of plates 83 and 84 mounted to slide in the ways 85 formed on the underside of said dial cap, and plates 83 and 84 are adapted to be actuated respectively by the links 86 and 87 through pins 88 and 88' secured to the plates 83 and 84 and working in slots 89 and 89' and formed in the body of the dial cap 82.

Plate 83 is constructed with a knitting cam 90 that acts to project the needles for knitting or tucking, and a flange 91 that limits their outward movement. Dial cap 82 has fixed thereto by screws 98 a retracting cam 198 adjacent one side of cam 90 that acts to retract the needles to draw their loops and cast off the knit loops of the form-

ing fabric. At the opposite side of cam 90 is a guard cam 197 that co-acts with cam 198 and flange 91 to hold the dial needles in idle position during reciprocating knitting on cylinder needles only, as for knitting 70 heels and toes of stockings.

On the other side of the dial from this group of cams is another similar group consisting of cams 90', 197', and 198'. Cam 90' acts, however, only to clear the latches of the needles for casting off the fabric from the dial needles or for opening the latches of the dial needles before taking yarn, no yarn being fed at this point. Flange 91' limits the outward movement of the needles, cam 197' retracts the needles after their latches are cleared by cam 90', thus casting off the rib stitches which are knit only by the dial needles, and cam 198' acts as a guard cam in the same manner and at the same time as cam 198. During reciprocatory knitting cams 197, 197' act only as guard cams to hold the needles in their inactive position.

A pair of guide members 95 pivotally mounted on studs or pins 96 (see Figures 7, 8, and 11) are tensioned, against projecting cams 90, 90' by the pair of springs 97, to the end of bridging the interval between the cams 90 and 90', irrespective of their adjusted positions and forming a smooth or unobstructed cam-way 92 through which the butts 93 of the dial needles 78 may move freely. Said pairs of guide members 95 are made movable to the end that they will give 100 and conform with the surfaces of the cams 90 in any position of said cams in their operation.

One of the principal obstacles to successful operation of machines for making tubular fabrics with sections of plain and ribbed fabric has been the inordinate amount amount of needle breakage in the dial due to the cams not being adapted to permit oscillatory movement of the rotary dial or the rotary dial cam plate. I avoid this difficulty in great part by providing a dial cam cap in which there are no parts projecting abruptly into the path of the needle-butts, each successive element on either side of cam-way 92 leading smoothly to the next, so that the needles cannot jam as in prior structures.

Another feature that appears to contribute largely to the successful practical operation of my device consists in that structure of the movable dial cams whereby I provide for adjustment of large segments of the cam-path, whereas prior constructions often moved only a small segment and that segment frequently on a pivot so that not only was the cam-path suddenly and radically distorted, but sudden and excessive movement was imparted to certain of the dial needles. Sometimes also but one wall 130

of the cam-path was adjustable, so that at the needle-projecting position undue clearance was afforded to the needle-butts during certain knitting operations. My dial structure avoids these defects, the needle-butts being under positive control at substantially all times and particularly when the needles are being projected or retracted, and the variations in travel of the needles being comparatively slow and easy by reason of the width of the movable segment, the needle path in the direction of movement of the needles being at all times smoothly curved, and without breaks on which the needle-butts might catch and cause a smash, said path being approximately circular when the dial needles are idle, and ovate when they are active.

Furthermore I have provided projecting cams for the needles which are symmetrical with respect to the diameter of the dial, thus making the adjustment of the plates 83, 84 easier, and helping to make the cam-path smooth and unbroken.

Another difficulty arises from the fact that the latches at certain times are likely to get out of the most favorable position and into the path of some part of the dial cap, when they are sometimes moved out of the way due to the cam action of such part of the dial on the pivoted latch, but also very often are broken off. Breakage of latches is much diminished in my machine by the provision of the narrow tapered J-shaped retracting cam coming to a point almost directly in front of the projecting cam at each side of the dial whereby partially opened latches on needles in idle position will be opened to the full extent.

It sometimes happens that the dial needles 78 become broken, and in order to facilitate their removal in such instances, and with the least trouble, an access passage, closed by the piece 99 (Figs. 7 and 8), is provided and said piece is detachably secured to the underside of the dial cap 82 by a spring-pressed stud 100 that works within a chamber 101 formed in said dial cap 82. Said stud 100 has a knurled head 94 for withdrawing the piece 99 into the recess 101 to give access to the needles.

The slide 83 is adapted to occupy various positions according to whether the needles are to knit, tuck or remain inactive in the "welting" position. In the last position the needles are idle and substantially stationary, but may either be empty, or be holding previously knit loops for making a welt.

The slide 84 also occupies different positions, depending on whether or not the needles are to be projected, as to clear the latches for casting off the work, or to open the latches prior to commencement of knitting on the dial needles, or opened prior to knitting on the dial needles.

The movement of the needles for casting off and latch opening is accomplished by the cam 90' connected to the link 86 and said link is connected to the arm 102 on the post or shaft 103 pivotally mounted in the block 71'. A pinion 104, secured to the shaft 103 meshes with a similar pinion 105 on the shaft 106, likewise journaled in said block 71', to the end that the movement of either shaft 103 or 106 will cause a like movement 75 of the other in the opposite direction. An arm 107 is mounted on the shaft 106 and acts, when engaged by the obstruction or trip 108, to move cam 90' to its outermost position, when the brush 109 on the support 110 on the sinker cam ring will engage the latches 111 of the needles to open the same. In this position of the cam, the dial head makes a suitable number of revolutions to insure that the latches of all of the needles 85 have been opened. An arm 113, on the shaft 103, co-acts with the obstruction or trip 108 to move the link 86 for carrying the cam half-way in; and immediately following this, the arm extension 115, engaging 90 the trip 108, moves the cam all the way in. The function of the arms 107, 113, and 115, is to co-act with the trip 108 for the purpose of positioning the cam 90' to project the needles to have the latches 111 opened, when 95 knitting is to begin on the dial needles and to move said needles fully in with said latches opened, thus leaving the needle hooks 112 in condition to receive the thread at the proper time; also to project and retract the 10 needles to throw-off the stitches when the fabric is to be cleared from the needles. The function of arms 117, 118 and 121 is to co-act with trip 114 to move the knitting cam into idle, tuck or knitting position according to the results desired.

The mechanism for controlling the knitting cam 90 (see Figures 2, 13, 14 and 15) consists of a shaft 116 journaled in the block 71, the shaft being normally moved in a direction to move the cam 90 into knitting position. A pair of spring-pressed latches or detents 117 and 118, here shown as hook-shaped, mounted on supports 119, are adapted to engage with a rockarm 120 fixed 11 to shaft 116 to hold the cam against the stress of the spring 116' in a half-way position, or fully in, as required. In their half-way position, i. e. when held by the latch 118, the hooks 112 of the needles receive the 12 thread as for forming tuck stitches. A rock-arm 121, also fixed to shaft 116, co-acts with the trip or stop 114 to move the cams all the way in. The two latches 117 and 118 are provided respectively with tails 122 and 123 12 that are engaged in succession by the trip 114 which permits the shaft 116 to actuate the link 87 and move the cams 90 and 91 into their outermost positions, i. e. the position for rib knitting.

A characteristic stocking made on my improved machine may consist of a ribbed leg; with a plain instep, sole, heel, and toe, such stockings being made in continuous succession as so-called string work, the successive stockings being separated by a number of courses of long loose stitches providing ravel courses at the point of separation. Fig. 1^a shows such a stocking in which there is a ribbed leg and a plain foot. The stocking may have, near its top a round welt or a flat welt in half cardigan stitch, the welts in the stocking here discussed being merely for purposes of ornament, and indicating some of the possibilities inherent in the machine.

The process of making such a stocking is as follows: Beginning at the toe, first, a toe pocket is knitted on the cylinder needles only, then the machine changes to a rotary movement for the foot which is knit in plain fabric on the cylinder needles. Then the heel pocket is knitted in the same manner as the toe pocket and a number of courses of plain fabric are knitted round and round following the heel.

To change from plain fabric in the foot to rib fabric for the leg, the dial needles are now advanced to open their latches, disk 108 being raised to engage arm 107 and move out cam 90'. The needles engage brush 109 as they advance, and the machine makes one or more revolutions so that all latches may be opened, the knitting cam 90 being at this time in retracted position. Disk 114 now engages arms 113 and 115 to return cam 90' to idle position and the dial needles are advanced at the knitting side of the machine to tuck position, disk 108 being raised to engage tail 122 to release hook 117, when the cam 90 and its plate will be moved by spring 116' toward knitting position, hook 118 engaging arm 120 on the shaft 116 to prevent the needles going all the way to knitting position. The dial needles now take the yarn and after all are supplied disk 114 engages arm 121 to return the needles to inactive or welting position, the latch 117 again engaging arm 120 on shaft 116 to hold the cam in place and the dial needles holding their stitches. The machine now makes one or more revolutions and then disk 114 is raised and releases latches 117 and 118 in two successive revolutions of the knitting cams to permit spring 116' to swing the post 116 to extreme position carrying cam 90 to knitting position. The purpose of taking the yarn by the dial needles a little prior to beginning rib knitting is to close the eyelet holes which otherwise would result at this point.

Rib knitting now continues throughout the leg up to the point where a tuck welt is to be made. At this point the disk 114 moves arm 121 so as to be caught by latch

118, the cam 90 being moved half way in and the dial needles now tucking while the cylinder needles knit as before. When each dial needle has taken one or more extra loops of yarn, the whole is knit off to form 70 a course of dial tuck stitches by raising disk 114 to release latch 118 so that cam 90 can knit, and this sequence of operation is repeated so long as tucking is to continue. A tuck welt or section of desired width having 75 been made, plain rib knitting is resumed, and thereafter a round welt is made by raising disk 114 to release both latches 117 and 118 in close succession, thus throwing the dial needles out of action but without casting off their loops. One or more courses are now knitted on the cylinder needles and the dial needles are returned to knitting position.

Rib knitting is resumed up to the top of 85 the leg. The change from rib to plain knitting on the cylinder needles is now made as follows:

Disk 114 is raised to strike arm 121 and move the cam 90 and the dial needles to 90 tucking position. After an additional revolution or two disk 114 strikes arm 121 and moves the cam 90 and the dial needles all the way in to inactive position, the shaft 116 being held by latch 117. The dial needles have now ceased knitting, but hold their loops. To cast off these loops, cam 90' is now operated, disk 108 actuating arm 107 to move casting off cam 90' all the way out to clear the latches of the dial needles, and 100 disk 108 then returning the cam by two steps by striking arms 113 and 115 in succession. Plain knitting is now resumed, the movement of the machine again being changed from rotary to oscillatory to begin the toe 105 of the next stocking.

Many variations may be made in the product of the machine by the use of my improvements, as such use is not limited to the making of stockings, being equally 110 applicable to machines for making underwear, sweater sleeves and other articles. Changes in the design of the article may also be made in numerous ways by varying the pattern devices to produce such effects as 115 may be desired.

It is to be noted that my machine is adapted to start knitting on the bare needles. In the ribbers commonly in use it is necessary to thrust the stitches of a piece of fabric on 120 both sets of needles to form a foundation on which knitting may begin one reason therefor being that the knitting waves of dial and cylinder needles are not simultaneous.

The presence in my machine of sinkers or 125 web holders such as are used in plain knitting machines enables me to start knitting on the bare needles without resorting to a transfer or stabbing-on of fabric.

The trip members 108 and 114 are mounted 130

on the shaft 124 to have vertical movement and rotation in the bearing 125 on the plate 126 secured to the frame 25. Said disks are adapted to be lifted for engaging the several arms 107, 113, 115, 121, 122 and 123 for adjusting the dial cams to cause the desired operations of the needles, in proper sequence, through the rod 127 working in the sleeve 128 and having a lateral portion 129 that engages the underside of the disk 114. The lower end of said rod 127 rests on lever 130 pivotally mounted on the frame 25 and which lever has a depending member 131 that co-operates with projections 132 that are located on the pattern wheel or form 133 which is mounted on the hub 134 of the ratchet wheel 45 the projections preferably being formed as removable screws or pins and being located at different distances from the hub to give the desired elevation to the trips. The ratchet wheel 45 is intermittently operated after the manner heretofore described; and said ratchet wheel operating means simultaneously moves the pattern wheel. The pattern wheel is constructed virtually as a mutilated ratchet wheel on which the pattern screws 132 and teeth 135 are located, leaving blank spaces. When the extension of pawl 49 rests on the blank space the pattern wheel remains stationary while the ratchet 45 drives the sprocket gear and its chain continually. When movement of wheel 133 is to be resumed one of a plurality of lugs 137 on chain 48 engages one of a plurality of lugs 136 on the wheel concentric with the series of pattern screws 132, moving it until pawl 49 can engage ratchet teeth on the pattern.

In the ordinary process of knitting hosiery, as carried out for example in the Mayo machine, the toe and heel portions of the foot are knitted with three threads, while the foot portion is knitted with only two threads; and for bringing the third thread into and out of operation, knitting machines have the yarn carrier adapted to be automatically actuated through a cam slot 138, formed in the cam wheel 65 on the shaft 44 (see Figures 1 and 5). Said cam slot 138 is usually provided with two salients, one for controlling the machine to knit the toe portion with three threads and move the yarn carrier out of position, and the other salient is to move the yarn carrier into position again for knitting the heel portion of the stocking with three threads, and then move the yarn carrier out of position when the body of the stocking is knitted with two threads. In ordinary plain knitting machines there are enough cylinder needles to form the foot portion (i. e. between the toe and heel) of sufficient texture for wearing, but in the present machine the number of cylinder needles is less than that on ordinary plain knitting machines by reason of

the dial needles, which must bear a definite ratio thereto. To compensate for the decrease in the number of needles used in plain knitting, I propose to use the three threads throughout the plain-knit heel, foot and toe, 70 as in Figure 1^a, instead of in the heel and toe only as in Mayo, thus giving a more uniform texture to the stocking.

To carry out the foregoing, it is therefore necessary to move the yarn carrier but once 75 into position, or when the foot of the stocking is to be formed. To this end the cam wheel 65 has but one salient 139, which acts on the shaft 140 (Fig. 4) of the yarn carrier (not shown) to move the latter into position 80 for knitting the entire foot portion of the stocking, and then to move the same out of position when the remainder of the stocking is being knitted. The mechanism of this machine is otherwise old and in common use, 85 the essential features being shown in the patent to Mayo, 726,229, April 21, 1903.

It is obvious that those skilled in the art may vary the details of construction and form and arrangement of parts without departing from the spirit of my invention, 90 and therefore I do not wish to be limited in any such features except as may be required by the claims.

Having thus fully described my said invention, what I claim as new and desire to secure by Letters Patent, is:

1. In a knitting machine, a dial cap having a radially movable projecting cam for the needles, a retracting cam and a guard cam, the projecting cam lying at one side of the path for the needle butts and the guard and retracting cams at the opposite side, and the latter cams being spaced from each other, and means moving with the projecting cam to close the space between the other cams, substantially as set forth.

2. In a knitting machine, a dial cam cap comprising a symmetrical needle projecting cam radially slidable to knitting and Welting positions, a needle retracting cam and a guard cam in spaced relation to each other, and means moving with the projecting cam to close the space between the other cams, substantially as set forth.

3. In a knitting machine, a dial cam plate having a needle-projecting cam, a fixed guard cam, and a tapered needle-retracting cam having an inwardly bent point extending approximately to the median line of the projecting cam, substantially as set forth.

4. In a knitting machine, a dial cam plate having a needle-projecting cam, a fixed guard cam, and a tapered needle retracting cam having an inwardly bent point extending approximately to the median line of the projecting cam, the needle projecting cam being movable from idle position to a plurality of yarn taking positions for the needles, substantially as set forth.

5. In a knitting machine, a dial cam plate having a narrow, tapered J-shaped retracting cam, a fixed cam and a symmetrical knitting cam located between the other cams and movable to knitting, tucking and welting positions, substantially as set forth.
6. In a knitting machine, a dial cam plate having a needle retracting cam, a fixed guard cam and a work-casting cam located between the other cams and slidably radially to latch clearing and idle positions for the needles, substantially as set forth.
7. In a knitting machine, a dial cam plate having knitting cams, and means for casting off the work including a cam slidable radially to latch clearing and idle positions, substantially as set forth.
8. In a knitting machine, a dial, a plate on the dial movable bodily toward and from the center of the dial and having a needle projecting cam fast thereto, and a flange also fast thereto adapted to limit the stroke of the needles, substantially as set forth.
9. In a knitting machine, a dial cap having thereon a needle retracting cam, a guard cam, a movable symmetrical needle-projecting cam therebetween, and a flange movable with the projecting cam and completing the external wall of the path for the needle-butts when the projecting cam is in idle position, substantially as set forth.
10. In a knitting machine, a dial cap having thereon a needle-retracting cam, a guard cam, a radially slidable needle projecting cam therebetween, and a flange movable with the needle projecting cam and completing the external wall of the path for the needle-butts when the projecting cam is in retracted position, substantially as set forth.
11. In a knitting machine, a dial cam plate having a diametrical groove, blocks thereon movable along said groove toward and from each other, a needle projecting cam on each block, fixed cams at the sides of said groove forming parts of the outer wall of a path for the butts of the dial needles, and means at all times closing the space between said needle projecting cams, substantially as set forth.
12. In a knitting machine, a dial cam plate having a groove, blocks thereon movable along said groove toward and from each other, a needle projecting cam on each block, fixed cams at the sides of said groove forming parts of one wall of a path for the butts of the dial needles, and means at all times closing the space between said cams, one of said fixed cams having a retractable portion providing a way for removal of broken needles, substantially as set forth.
13. In a rib knitting machine, a dial cam cap, a pair of oppositely located radially slidable dial cams, a needle retracting cam at one side of each slidable cam having a narrow tapered formation with its point substantially in line with the corresponding slidable cam and a guard cam at the other side of each slidable cam, substantially as set forth.
14. In a knitting machine, a dial cam cap comprising a slidable needle-projecting cam movable to knitting and welting positions, a needle retracting cam at one side of the knitting cam and a needle projecting cam at the opposite side of the cam cap movable to idle or to work-casting position and pattern mechanism for positioning the projecting cams independently of each other, substantially as set forth.
15. In a knitting machine, a dial cam plate, diametrically opposed cams thereon movable toward and from each other, fixed cams coacting with said movable cams to provide a smoothly curved substantially circular path for the needle-butts when the needles are idle and a substantially ovate path when active, and automatic means to position said movable cams, substantially as set forth.
16. A dial cam cap having a knitting cam movable to tucking and welting positions, a narrow, J-shaped needle retracting cam at one side of the knitting cam, a guard cam at the other side and a needle projecting cam at the opposite side of the dial from the knitting cam adjustable to idle and work-casting positions.
17. In a knitting machine, dial needles, a rotating head, cams carried by the rotating head adapted to actuate the dial needles, means to move the cams to vary the interval therebetween, and spring pressed fingers engaging the surfaces of the cams and serving to bridge the intervals between the cams irrespective of the position of the cams relative to each other, substantially as set forth.
18. In a knitting machine, dial needles, a rotating head, cams carried by the dial disposed upon opposite sides of the axis of rotation, one of said cams being adapted to throw the dial needles into and out of knitting position, the other cam being adapted to throw the needles at a point removed from knitting position, means to move either of said cams independently toward and from the axis of rotation, and yieldable bridging devices spanning the intervals between the cams irrespective of their adjusted position, substantially as set forth.
19. In a knitting head, the combination of a dial plate adapted to be mounted on a knitting machine, a plurality of radial dial needles mounted to operate in said dial plate, a shaft operable in said dial plate, a dial cap fixedly mounted on said shaft, a pair of diametrically opposed plates slidably mounted in the dial cap, a pair of cams carried by said plates for projecting the dial needles, movable guide members associated with the dial needles, and a dial cam plate having a groove, blocks thereon movable along said groove toward and from each other, a needle projecting cam on each block, fixed cams at the sides of said groove forming parts of the outer wall of a path for the butts of the dial needles, and means at all times closing the space between said cams, one of said fixed cams having a retractable portion providing a way for removal of broken needles, substantially as set forth.

- with said projecting cam elements, a second pair of cam elements for retracting said needles, fixed needle guide members co-operable with said retracting cam elements, a member secured to the shaft for actuating the same, and operative connections for said cam carrying plates, substantially as set forth.
20. A dial cap for a knitting machine comprising a needle cam movable to idle position and to a plurality of yarn-taking positions, a spring to impel the cam in one direction, a plurality of latches to hold the cam in different positions and means to release said latches including a pattern mechanism, substantially as set forth.
21. A dial cap for a knitting machine comprising a needle cam movable to idle position and to a plurality of yarn-taking positions, a spring to impel the cam in one direction, a plurality of latches to hold the cam in different positions, means to release said latches, means to restore the cam against the tension of the spring, and a pattern mechanism to operate both said means, substantially as set forth.
22. The combination with a plain knitting machine of an attachment therefor for rib knitting comprising an actuating cam element for the needles thereof, a spring controlled device for positioning the cam element, a pair of latches for holding said device in positions for different knitting operations, a trip for releasing said latches, means for actuating said trip, and a pattern form associated with said trip actuating means, substantially as set forth.
23. The combination with a plain knitting machine of an attachment therefor for rib knitting comprising an actuating cam element for the needles thereof, a spring controlled device for positioning the cam element, a pair of latches for holding said device in positions for different knitting operations, tripping means for releasing said latches successively and for restoring said device against the spring action, means for positioning said tripping means, and a pattern form associated with said positioning means, substantially as set forth.
24. The combination with a plain knitting machine of an attachment therefor for rib knitting comprising an actuating cam element for the needles thereof, a rockshaft for positioning the cam element, an arm on the shaft, a spring tending to rotate the shaft in one direction to position the cam element, latches for holding the rockshaft in positions for different knitting operations, tripping means for releasing said latches and for engaging said arm to move the shaft against the action of the spring, and means for actuating said tripping means in timed relation including a pattern form, substantially as set forth.
25. The combination with a plain knitting machine of an attachment therefor for rib knitting comprising an actuating element for the needles thereof, a spring controlled device for positioning the cam element, means for holding said device in positions for different knitting operations of the dial needles and pattern-controlled means for releasing the holding means successively, substantially as set forth.
26. In a knitting machine, adapted for knitting integral sections of rib fabric and plain fabric with pouch-like enlargements, two sets of needles, means for operating the needles, means for imparting relative rotary and oscillatory movement to the needles and their operating means, the operating means comprising radially movable needle projecting cams, needle retracting cams, and means movable with the projecting cams and co-acting with the retracting cams to form a smooth outer wall for the path of the needle butts in one position of said projecting cams, substantially as set forth.
27. In a knitting machine, two sets of needles, operating means therefor, pattern mechanism to control the operation of the machine to produce ribbed, plain circular or reciprocating work, said operating means comprising a dial and a dial cap, a needle projecting cam slidable thereon to and from idle position and means movable therewith to limit the throw of the needles, said pattern mechanism controlling the position of said cam, substantially as set forth.
28. In a knitting machine, two sets of needles, operating means therefor, pattern mechanism to control the operation of the machine to produce ribbed, plain circular or reciprocating work, said operating means comprising a dial and a dial cap, a needle projecting cam radially slidable thereon to and from idle position and means movable therewith to limit the throw of the needles, said pattern mechanism controlling the position of said cam, substantially as set forth.
29. In a knitting machine, two sets of needles, operating means therefor, pattern mechanism to control the operation of the machine to produce ribbed, plain circular or reciprocating work, said operating means comprising a dial and a dial cap, a needle projecting cam slidable thereon to idle position and a plurality of yarn-taking positions, and means movable therewith to limit the throw of the needles, said pattern mechanism controlling the position of said cam.
30. In a knitting machine, two sets of needles, operating means therefor, pattern mechanism to control the operation of the machine to produce ribbed, plain circular or reciprocating work, said operating means

comprising a dial and a dial cap having a cam set consisting of a needle projecting cam movable to idle position and to a plurality of yarn taking positions for the needles, a pointed J-shaped retracting cam and a guard cam, said pattern mechanism controlling the position of said needle projecting cam, substantially as set forth.

31. In a knitting machine, two sets of needles, operating means therefor, pattern mechanism to control the operation of the machine to produce ribbed, plain circular or reciprocating work, said operating means comprising a dial and a dial cap having guides thereon, a slideable plate held in place by said guides, and carrying a needle projecting cam and a flange, said pattern mechanism also controlling the position of said cam, substantially as set forth.

32. In a knitting machine, two sets of needles, operating means therefor, pattern mechanism to control the operation of the machine to produce ribbed, plain circular or reciprocating work, said operating means comprising a dial and a dial cap, needle projecting cams at opposite sides thereof, each independently radially movable to and from idle position, a tapered J-shaped retracting cam and a guard cam for each projecting cam, said pattern mechanism also controlling the movement of said projecting cams, substantially as set forth.

33. In a knitting machine, two sets of needles, operating means therefor, pattern mechanism to control the operation of the machine to produce ribbed, plain circular or reciprocating work, said operating means comprising a dial and a dial cap having a cam set consisting of a needle projecting cam movable to idle position and to a plurality of positions wherein the needles may take yarn, a pointed J-shaped retracting cam and a guard cam, and an oppositely placed set of cams consisting of a needle projecting cam movable to idle and work-casting positions, a pointed J-shaped retracting cam and a guard cam, said pattern mechanism controlling the movement of said needle projecting cams, substantially as set forth.

34. In a knitting machine, two sets of needles, operating means therefor, and pattern mechanism to control the operation of the needles to produce ribbed, plain circular or reciprocating work, said operating means including dial cams certain of which are radially slideable under control of said pattern mechanism, and said dial cams providing in active position a cam path with continuous smoothly curved, substantially ovate walls at each side thereof, substantially as set forth.

35. In a knitting machine, two sets of needles, operating means therefor, pattern mechanism to control the operation of the needles to produce ribbed, plain circular or

reciprocating work, said operating means including a dial cam plate, cams thereon forming a path for the needle butts and including encircling guard cams providing an outer wall and needle-projecting cams movable to vary said path, the path being circular in idle position and ovate without abrupt curves when the needles are active, substantially as set forth.

36. In a knitting machine, two sets of needles, operating means therefor, pattern mechanism to control the operation of the needles to produce ribbed, plain circular or reciprocating work, said operating means including dial cams certain of which are diametrically opposed and radially slideable toward and from each other under control of said pattern mechanism, and said dial cams providing in active position a cam path with continuous smoothly curved substantially ovate walls at each side of said path thereof, substantially as set forth.

37. In a knitting machine, two sets of needles, means for operating the needles, and means to control the operation of the needles to produce ribbed, plain circular or reciprocating work, a dial cam cap, having oppositely slideable needle projecting cams, guard cams slideable therewith and independent guard and needle retracting cams coacting with said first-named guard cams to limit outward movement of the needles, the successive cams in the direction of needle-travel merging smoothly into each other and providing a cam path without angles or abrupt changes of direction, in all positions of said movable cams, substantially as set forth.

38. In a knitting machine, two sets of needles, operating means therefor, and pattern mechanism controlling said means to knit integral sections of rib fabric and plain fabric with pouch-like enlargements, said operating means including a dial cam cap, a needle-projecting cam under control of said pattern mechanism movable to active and inactive positions, said cam having its outer end rounded and the cam being symmetrical relative to a diameter of the cam cap when in idle position, substantially as set forth.

39. In a latch needle knitting machine, a dial cam cap having a needle projecting knitting cam, a needle projecting casting off cam, a retracting cam adjacent to each of said projecting cams, and means on the retracting cam adjacent to the casting off cam for fully opening partially opened latches on the knitting needles, substantially as set forth.

40. In a dial and cylinder knitting machine, dial and cylinder needles, operating means therefor, pattern mechanism causing said operating means to rotate or reciprocate for knitting ribbed, plain circular or reciprocating work, dial cams for actuating

one set of needles including a needle projecting knitting cam movable from idle position to plain knitting position, a needle projecting casting off cam movable from idle to latch-clearing position, and a retracting cam adjacent each projecting cam constructed and arranged to open fully the partially closed latches of needles in idle position at that point, substantially as set forth.

41. In a dial and cylinder knitting machine, dial and cylinder needles, operating means therefor, pattern mechanism causing said operating means to rotate or reciprocate for knitting ribbed, plain circular or reciprocating work, dial cams for actuating one set of needles including one or more needle projecting cams, means actuated by said pattern mechanism to withdraw said cams into idle position during reciprocatory knitting, and a needle-retracting cam adjacent to each projecting cam adapted to lay back partly closed latches on the knitting needles, substantially as set forth.

42. In a knitting machine, dial needles, a rotating head, cams carried by the rotating head upon opposite sides of its axis and adapted to throw the dial needles, means to move the cams independently toward and from the axis of rotation, and bridge members flexibly engaging the surfaces of the cams and spanning the intervals between the cams, substantially as set forth.

43. The combination with a plain knitting machine of an attachment therefor for rib knitting comprising an actuating cam element for the needles thereof, a spring controlled device for positioning the cam element, means for holding said device in positions for different knitting operations of the dial needles, and pattern-controlled means adapted to release the holding means and also adapted to restore said positioning device to the control of the holding means, substantially as set forth.

44. A dial cam mechanism comprising a dial cap, blocks mounted to move radially upon the dial cap, cams carried by the blocks each presenting an external rib and an internal member conforming to a portion of an ellipse, members spanning the interval between the sliding members and forming the sides of an ellipse, and means to hold the members yieldingly in engagement with the internal cam portions.

45. In a dial and cylinder knitting machine, dial and cylinder needles, operating cams therefor, and pattern mechanism causing relative rotation or reciprocation between the needles and the operating means said cams including needle projecting cams

at opposite sides of the dial movable toward and from the center of rotation and means yieldably engaging the surfaces of the needle projecting cams and spanning the intervals between them, substantially as set forth.

46. In a knitting machine, a stationary needle cylinder, a needle dial, dial and cylinder cams adapted to rotate or oscillate for knitting tubular articles having pockets, lugs on the interior of the needle cylinder approximately at opposite sides thereof, and a single lug on the dial adapted to strike alternately against the cylinder lugs during oscillatory knitting, substantially as set forth.

47. The combination with a plain knitting machine of an attachment therefor for rib knitting comprising an actuating cam element for the needles thereof, a spring controlled device for positioning the cam element, vertically spaced latches for holding said device in different positions of operation, a trip, and means for elevating said trip to different heights to release said latches, substantially as set forth.

48. In a knitting machine, dial needles, a rotating head, cams carried by the rotating head upon opposite sides of its axis and adapted to actuate the dial needles, means to move the cams independently toward and from the axis of rotation, and bridge members yieldably engaging the surfaces of the cams and spanning the intervals between the cams, substantially as set forth.

49. In a latch needle knitting machine, a dial cam cap having a needle projecting knitting cam, a needle projecting casting off cam, a retracting cam adjacent to each of said projecting cams, and means underneath the dial cam cap in advance of the retracting cam adjacent to the casting off cam for fully opening partially opened latches on the knitting needles, substantially as set forth.

50. In a knitting machine, a stationary cylinder needle holder, a dial needle holder, dial and cylinder cams adapted to rotate or oscillate for knitting tubular articles having pockets, a pair of lugs on one of said holders approximately at opposite ends of a diameter of such holder, and a single lug on the other holder adapted to strike alternately against the first named lugs during oscillatory knitting, substantially as set forth.

In witness whereof, I have hereunto set my hand at Washington, District of Columbia this 9th day of January, A. D. nineteen hundred and seventeen.

NAPOLEON J. PERRY.
